UNITED STATES PATENT OFFICE.

BERNARD HUGO MUEHLE, OF DETROIT, MICHIGAN.

HYDRAULIC DREDGE.

SPECIFICATION forming part of Letters Patent No. 623,804, dated April 25, 1899.

Application filed December 6, 1897. Serial No. 660,931. (No model.)

To all whom it may concern:

Be it known that I, BERNARD HUGO MUEHLE, a citizen of the United States, residing in the city of Detroit, in the county of Wayne and State of Michigan, have invented a new and useful Improvement in Dredges, of which the following is a specification.

My invention relates more particularly to certain improvements in hydraulic dredging-machines used for removing sand and other material from the bottoms of rivers and lakes by means of a suitable excavating device, as through a suction-tube, onto and beyond a floating hull or vessel by means of a rotary or other pump; and the objects of my invention are, first, the application and use of one or more traction-wheels traveling on the river-bottom and connected with the dredge-machinery for the purpose of propelling the dredge-boat and moving the suction-pipe in any desired direction; second, the combination and arrangement of one or more traction-wheels connected with one end of the dredge-hull and an axial spud at the other end, so that the dredge-hull may be propelled and the cutting edge or mouth of the suction-pipe be introduced into the material to be dredged on the arc of a circle the center of which is the point of the axial spud, and, third, providing a suitable mechanism for revolving the traction-wheels which may be operated and connected with steam-power on the dredge-boat.

In the accompanying drawings, Figure 1 is a perspective view of a dredge, showing the general features of my invention. Fig. 2 is a front elevation of a spud, traction-wheel, and operating mechanism. Fig. 3 is a side elevation of the same. Fig. 4 is a rear elevation of the same. Fig. 5 is a horizontal section of the spud on line 1 2; and Fig. 6 is a horizontal section on line 3 4, the top view of the operating mechanism.

Similar letters refer to similar parts in each of the figures.

The stern or rear portion of the dredge-hull A is preferably constructed in two separated parts, so as to form a narrow longitudinal recess or opening B, and the opposite end or bow is provided with a vertical spud or anchoring device C.

D is the suction-tube, shown connected with the pump on the vessel by means of a

flexible joint d, which permits the suction end or mouth of the tube to be let down between the walls of the recess or opening, so that when adjusted in its lowest possible position on the river-bottom it will be nearly below the end of the hull. The suction-tube should fit snugly within the opening, so that when the stern of the dredge is moved or swung sidewise the tube will move with it.

Fig. 1 of the drawings shows upon each side of the opening B at the stern of the vessel a spud E, usually made of square timber, which is held perpendicularly between adjustably-flanged guide-rollers e e or their equivalents. Each spud may be raised by means of a rack and pinion or other suitable device, which permits it to drop down by its own weight when required and to freely rise and fall within its bearings.

A traction-wheel F is hung in a frame g, bolted to the lower end of the spud. The projections f upon the outer face or circumference of the wheel may be made of any shape or size which will insure their penetration into or taking firm hold of the bottom of the river, and for this purpose traction-wheels especially designed for either sand bottom, gravel, clay, or other material should be kept on hand on board of the dredge and put into use as occasion requires. The face of each traction-wheel should be tangential to the arc of a circle the center of which is the point of the spud C, so that when the wheels are revolved by means of the mechanism herein-after described the stern of the dredge is propelled with a circular motion around the spud C, thereby forcing the suction end of the tube lying on the bottom into the bank of the material to be dredged.

The mechanism for revolving the traction-wheels consists in a spur-wheel H and pinion h or their equivalents, the former secured to or forming part of the wheel F and the latter keyed upon a counter-shaft carrying a chain wheel or pulley K, all of which parts are supported upon the frame g. An endless chain or cable L connects the pulley K with a similar wheel k' at the extreme upper end of the spud E. Each of the perpendicular reaches of this endless chain is wound once around a drum on each side of the spud. These drums m and m' revolve freely each

- around its shaft, the latter having their bearings on a framework n , bolted to and overhanging the edge of the deck of the dredge. Each drum is bolted to a spur-wheel p , 5 which is geared to a pinion r , the latter revolving loosely upon the shaft O . This shaft carries a pulley q and fly-wheel q' and is connected by means of a chain, belt, cable, or other suitable device with the main shaft 10 of the engine which operates the pump or that of an auxiliary engine located below the shaft O in the hold of the dredge at a' . Between the pinions r , the shaft O also carries a clutch S , which is operated by means of a 15 lever t and, sliding upon a feather, revolves with the shaft. When the lever is held perpendicular, as shown in Fig. 4, and the clutch is in contact with neither of the pinions on the shaft O , the spud E may be raised, while 20 the endless chain L causes the drums m , spur-wheels p , and pinions r to revolve in one direction, or the spud may be lowered until the traction-wheel rests on the river-bottom, this downward movement causing 25 the drums, spur-wheels, and pinions to revolve freely in the opposite direction. After the spud and traction-wheel have reached the bottom, the axial spud C dropped into position, and the suction end of the tube D adjusted at the necessary level to insure the 30 required depth of excavation in the proposed channel the pumping-engine is started, and in order to force the suction end of the tube into the bank of material to be dredged the stern of the dredge is moved laterally, swinging around the axial spud C in the following manner:
- The operator having first connected the shaft O with the motive power, so as to 35 revolve the shaft and the clutch S , he then moves the lever t so that the clutch comes into contact and unites with the pinion r . Rotary motion and power are thus transmitted through the spur-wheel p , drum m , endless 40 chain or cable L , pulley K , and gearing H to the traction-wheel F in such manner that the revolution of this wheel upon the bottom of the river causes the dredge-hull, and with it the suction-tube D , to be propelled in the 45 desired direction while the excavation by the suction through the tube is in progress in the usual and well-known manner. Thus the river-bottom is leveled to the required depth on the arc of a circle the center of which is 50 the point of the spud C . When the suction end of the tube D has reached the limit of the proposed channel width, the operator reverses the lever t , bringing the clutch into contact with the pinion r' , thereby transmitting 55 power through the spur-wheel p' , drum m' , endless rope or chain L , pulley K , and gearing H to the traction-wheel F , so as to propel the dredge and move the suction end of the tube D in the opposite direction.
- 60 Although it is expected that the weight of the spud E will be sufficient to secure the necessary penetration of the projections upon

the traction-wheel and cause the latter to take a firm hold on the river-bottom, yet the operation of the mechanism above described is such that the transmission of power through the endless rope or chain, no matter which of the drums m , m' is revolved for that purpose, will produce a downward strain upon the endless rope or chain L , which strain is greater or less as the power required to propel the traction-wheel and move the dredge-hull or to force the suction-tube into the bank of material to be dredged is either increased or diminished.

The diameters of the spur-wheels H , p , and p' and the pinions h , r , and r' should be so proportioned that the high speed of the driving-shaft O is transmitted through this gearing, so as to produce the necessarily slow revolution of the traction-wheel and the power required to force the suction-tube into the material to be dredged. To that end an additional train of gear-wheels may be interposed, if necessary, either upon the spud E or between the shafts O and the drums m , m' , or both.

A pair of small propeller-wheels w are hung upon horizontal shafts projecting from the stern of the dredge and connected by means of a clutch arrangement or other device with the main driving-shaft of the engine. These wheels are used for propelling the dredge, placing it in position, and aiding, when necessary, in making the regular shifts of the dredge-hull along the axis of the proposed dredge-cut.

The operation of my improved dredge here-with shown and described is as follows: All the spuds being raised and the suction-tube adjusted in a horizontal position, the dredge is afloat and may be propelled by means of the stern-wheels w to the place where the channel is to be deepened. When the bow has reached the initial point in the axis of the proposed channel, the spud C is dropped to the bottom of the river, so that the sharp point penetrates the soil sufficient to hold that end of the dredge-hull firmly in place. Then the latter is swung around into alignment with the axis of the channel, the spuds permitted to slide to the bottom, and the suction-tube lowered and adjusted so that its mouth is on the level of the grade to which the channel is to be excavated. The pump being started, excavation of the material is commenced. The operator then moves the lever t so as to connect the clutch S with either of the pinions r or r' , thereby revolving the traction-wheels F and moving the dredge laterally, forcing the suction-tube into the material to be dredged, as hereinabove described, on the arc of a circle the center of which is the spud C . After one of the side lines or limit of the proposed channel has been reached the motion of the dredge and suction-tube is reversed and the other half of the channel excavated in like manner. In order to make the next concentric dredge-cut, the dredge is

- moved along the axis of the channel after raising all the spuds by propelling the vessel in the desired direction the required distance and again dropping the spuds to the bottom.
- 5 In rivers where there is a current and where it is found to be expedient to work downstream the dredge may be held by an anchor, as shown in Fig. 1, and the anchor chain or cable slackened and paid out the required 10 length; but in still water a few revolutions of the wheels W will answer the same purpose. In both cases it will be advisable to use a "trailing" spud to prevent a lateral movement of the bow of the vessel.
- 15 My improvements as applied in the construction of the smaller class of dredges may be modified by omitting the recess or opening B and suspending the suction-tube along the side of the vessel, by using but one spud.
- 20 E with traction-wheel and its operating mechanism at the stern, and by substituting for the spud C and trailer at the bow of the dredge another spud E with a traction-wheel which may be turned so as to move the dredge along 25 the axis of the proposed channel.
- The advantages of my invention consist, mainly, in economical construction and simplicity of operation. By means of the lateral movements of the stern of the dredge around 30 a pivotal spud at the bow a greater width of channel may be dredged to grade at each forward shift of the dredge along its axis, said width being limited only to twice the distance between the pivotal spud and the mouth of 35 the suction-tube. There being no side lines leading to anchors or other fixed points—the method now used for holding dredges in position—work can be carried on without obstruction to navigation in at least one-half 40 of the channel being dredged, and if the material is deposited in dump-scows, which may be placed at the bow of the dredge, then the channel on either side of the dredge may be used by passing vessels alternately while the 45 channel improvement is in progress. The lateral movement of both dredge and mouth of suction-tube, by means of the traction-wheels traveling on the river-bottom after it has been leveled, may readily be controlled 50 and its speed regulated by an attendant on board of the dredge. Both the lateral movement, as well as the regular shifts of the dredge along the axis of the channel, may be made without interrupting the work of excavation.
- 55 While I have shown and described my invention as relating more particularly to a hydraulic dredge, it is evident that the same is also applicable to elevator and other forms of dredges.
- 60 Having fully described my invention, what I claim, and desire to secure by Letters Patent of the United States, is—

1. A dredge-hull provided with an upright

spud at or near one end, and a traction-wheel carried by said spud, said traction-wheel constructed and arranged to travel on the river or analogous bottom transversely of said hull, whereby the end of the dredge-hull to which the traction-wheel is engaged may be moved laterally, substantially as set forth. 65

2. A dredge-hull provided with an anchoring device at one end, and with an upright spud at or near the opposite end of the hull, a traction-wheel carried by said spud arranged to travel on the river or analogous 75 bottom, and means to cause said traction-wheel to travel transversely of the hull, whereby the end of the dredge-hull to which the traction-wheel is engaged may be moved laterally, substantially as set forth. 7c 80

3. A dredge-hull provided with a pivotal spud located at or near one end of the hull and spuds located at or near the opposite end of the hull provided with traction-wheels arranged to travel on the river or analogous 85 bottom transversely of said hull, whereby the hull may be moved laterally about the pivotal spud, substantially as described.

4. A dredge-hull provided with an anchoring device located at or near one end of the 90 hull, a traction-wheel located at or near the opposite end of the hull arranged to travel on the river or analogous bottom, means to cause said wheel to travel transversely of said hull, whereby the dredge-hull may be moved laterally, and an excavating device located at 95 or near the end of the hull carrying the traction-wheel, substantially as described. 95

5. A dredge-hull provided with a pivotal spud located at or near one end thereof, and 100 with additional vertically-adjustable spuds located at or near the opposite end of the hull provided with traction-wheels arranged to travel on the river or analogous bottom transversely of the hull, and means to actuate said 105 wheels, substantially as described.

6. A hydraulic dredge having a vertically-adjustable suction-tube D, and moving around a pivotal spud C by means of one or more traction-wheels F upon spuds E, substantially as herein described. 110

7. The combination of the spud E, traction-wheel F, gearing H, h, chain wheels or pulleys K k, endless rope or chain L, and drums m, m', all parts arranged and operating, substantially as set forth. 115

8. The combination of the traction-wheel F, gearing H h, chain-wheels K k, endless rope or chain L, drums m, m', gearing p, p' and r, r' and clutch S, all parts arranged and operating, substantially as herein described. 120
